UNITED STATES PATENT OFFICE.

WILLIAM CAMERON, OF CHICAGO, ILLINOIS, ASSIGNOR TO CAMERON CAN MACHINERY COMPANY, OF CHICAGO, ILLINOIS, A CORPORATION OF ILLINOIS.

DOUBLE-SEAMING MACHINE.

Application filed March 22, 1923. Serial No. 326,733.

This invention relates to machines for applying can ends, either tops or bottoms, to can bodies. While the machine shown and described as illustrative of the principles of my invention is a double-seaming machine, adapted to double seam curled ends onto flanged can bodies, it should be understood that the principles of the invention may be embodied in machines for applying straight flanged ends.

Furthermore, while the machine herein disclosed is particularly desirable for capping filled cans, since it is adapted to handle the cans with a minimum of agitation and slopping of the liquid contents of the cans, the machine may, if desired, be employed for applying ends to unfilled cans, or to tubular can bodies which have not been previously equipped with either top or bottom.

One of the primary purposes of this invention is to provide a machine capable of performing the functions indicated, which will be capable of applying ends to cans at a much higher speed than machines heretofore employed for this purpose.

The machine is furthermore extremely simple in construction possessing fewer moving and operating parts than has heretofore been considered necessary in machines of this character, and because of its simplicity, it is extremely accurate and reliable in operation and is also very durable.

In addition to the features mentioned, a machine embodying my invention is capable of being quickly and accurately adjusted by manipulation of a single adjusting device, whereby the machine may be almost instantly adjusted to accommodate can bodies of various heights.

Another feature of the invention resides in novel means for feeding the can bodies and spacing them in the desired relation before they enter the machine proper, and in this connection it may be mentioned that the general design of the machine is such that the bodies may be spaced much closer together than has heretofore been considered possible, thereby enabling a greater number to be fed through the machine in a given length of time than could be fed if they were spaced farther apart.

Another feature resides in novel mechanism for truing or rounding up the can bodies so as to make them truly circular in form in order that they may readily enter the circular flange caps.

A further and very important feature of this invention is the provision of novel seaming mechanism whereby the can ends are secured to the can bodies. In the form of the invention shown this mechanism is adapted to double seam curled ends onto flanged bodies, although the application of straight flanged ends is contemplated as being within the scope of my invention. This novel seaming mechanism obviates entirely the employment of the usual seaming rollers which are designed to revolve around the stationary bodies and caps for the purpose of performing double seaming operations. The elimination of these revolving rollers, their carriers and the mechanism for revolving the same, greatly simplifies the construction of my present machine and enables it to be built much smaller and more compactly than previous machines of this general character.

Another object of the invention is to provide novel and improved mechanism for feeding the caps from a magazine to the point of application to the can bodies, which mechanism includes a novel no can, no cap control, which precludes the feeding of caps in the event of failure or absence of can bodies.

Another object is to provide an automatic marking device by means of which the caps are marked with any desired number, letter or character during their travel from the magazine to the point of application to the can bodies.

Further features of the invention reside in the provision of novel means for positively ejecting the capped cans from the spindle chucks, means for positively depressing the cam followers which serve to elevate the can bodies and caps into engagement with the chucks, means for stopping the rotation of the can body supporting plates after the completion of the seaming operation, and means incorporated in the can raising mechanism whereby a can body may be

lowered for inspection after its passage through the first set of seaming rolls.

Other objects and many of the inherent advantages of this invention should be readily appreciated as the same becomes better understood by reference to the following description when considered in connection with the accompanying drawings.

Before referring specifically to the drawings, a brief description of the general functions and operation of the machine may facilitate an understanding of the invention. At one side of the machine the can bodies, either filled or unfilled, as the case may be, are advanced toward the machine by an endless carrier on which, near the delivery end thereof, the bodies are automatically spaced the requisite distance apart by novel spacing mechanism. The bodies then successively enter a star wheel which revolves in peripheral proximity to a spider provided with peripheral body receiving pockets. The pockets of the spider in conjunction with the companion pockets of the star wheel serve to true or round up the bodies so that their upper edges may be introduced into the flanged caps disposed directly above the bodies. The caps are fed from a magazine to the spider, on which they are clamped and held in position over the pockets so as to be in exact alignment with the can bodies in the pockets. During the travel of the can ends from the magazine to the spider, the can ends pass a marking station at which a suitable character or mark is automatically applied to the ends. A can end and body having been aligned as explained, the body is now lifted to project its upper end into the flange of the end, whereupon the body with the end thereon is further elevated to press the end firmly against a revolving spindle chuck. The body is supported at its lower end upon a freely rotatable plate, and as the end is brought into engagement with the revolving chuck, a rotary movement is imparted to the can end and body until they are spinning at a relatively high rate of speed. The spinning bodies are then carried forward by the continuously revolving spider, bringing the periphery of the can end into engagement with the primary seaming mechanism comprising one or more freely rotatable seaming rollers. When a pair of rollers as shown is employed the distance between these rollers is slightly less than the initial diameter of the can end, and as the rapidly spinning end is urged against these rollers, the margin of the end will be bent or curled downwardly and inwardly until the diameter is reduced to the distance between the rollers, whereupon the can body and end will pass between these rollers. The partially seamed end then engages a second or final seaming mechanism shown

as comprising a pair of seaming rollers, set closer together than the previous pair, although only one roller may be employed if preferred. By this second seaming mechanism the completion of the double seaming operation is performed, so that when the can with the end thereon passes this mechanism, the end is securely double seamed to the body. The body with the end secured thereto is then discharged from the machine in the usual manner.

With this brief description of the general operation of the machine, reference will now be had to the drawings for a more detailed disclosure thereof.

Referring to the drawings:

Frame construction.

From an inspection of the drawings it will be observed that the entire machine is supported upon a hollow, inverted base 25, carrying at one side the feed table 26 along which the can bodies are fed into the machine, and at the opposite side, upon an adjustable post 27, a delivery table or chute 28 upon which the capped bodies are discharged from the machine. At the back of the machine there is mounted upon the base 25, as will be apparent from Figs. 2 and 3, a hollow pedestal 29, in which the lower portion 31 of a side column is telescopically mounted for vertical adjustment. Upon this column portion 31 is mounted a box or casting 32, housing certain mechanism which will be later described, and surmounting the box is the upper portion 33 of the side column which is laterally bent at its upper end, as shown in Figs. 2 and 3. A center column 34 is rotatably supported near its lower end upon ball bearings 35 carried by a vertically movable adjusting member 36. Vertical movement of this column relatively to the adjusting member is precluded by a lock nut 37 threaded onto the lower end of the column, this nut being split throughout a portion of its periphery and equipped with a set screw 38 by which the nut may be spread and locked to the column. An upper spider or spindle carrying head 39 is secured by a key 41 to the upper end of the center column. A hollow supporting standard 42, carried by the base 25, is shaped to surround the adjusting member 36 and also a portion of the column 34, and upon a shoulder 43, formed around this standard, a lower spider 44 is rotatably supported. The weight of this spider is carried upon a bearing ring 45, and the spider is held against upward displacement by a flanged retaining ring 46 secured to the bottom thereof, and engaged in a circumferential groove in the standard 42, as will be apparent from Figs. 2 and 8. To prevent the entrance of liquid, dirt and other foreign matter into the spider bearing, a sealing ring 47 is fitted snugly around the column 34 and secured by screws or otherwise to the spider, and a ring of packing material 48 is interposed between the lower face of this ring and the upper end of the standard 42.

Driving mechanism.

Referring now to Figs. 1 to 3, inclusive, it will be observed that the machine is driven

by power applied from any suitable source to a belt pulley 49, loosely mounted on a shaft 51, to which a driving connection is established through a clutch 52 of any preferred construction adapted to be manually controlled from the front of the machine through a hand lever 53, connected by a link 54 to an arm 55 fixed upon a rock shaft 56, which has fixedly mounted on its other end a clutch actuating yoke 57.

Within the base 25 the drive shaft 51 is provided with a gear 58, which meshes with and drives a gear 59, keyed to a cross-shaft 61. A bevel gear 62, also fixed on the shaft 61, meshes with and drives a companion gear 63 so fixed, together with a spur gear 64, upon the lower end of a hollow shaft 65, journaled in a bearing 66 and held against endwise displacement by a lock nut 67 threaded onto the upper end of the hollow shaft. A vertical shaft 68, having its lower end telescopically projecting into the hollow shaft 65 and splined thereto by means of a driving spine 69, extends upwardly from the base through the housing 32, where within the housing it carries the cams 71 and 72, and above the housing the cam 73, the functions of which cams will be later explained.

A second vertical shaft 74, mounted in upper, intermediate and lower bearings 75, 76, and 77, respectively, (Fig. 3) has keyed to its lower end a gear 78 which meshes with and is driven by the gear 64. A pinion 79, keyed to the shaft 74, meshes with and drives a ring gear 81 fixed upon the perimeter of the spider 44, and by which rotary movement is imparted to the spider. A second pinion 82, splined to the upper portion of shaft 74 so as to be capable of vertical movement with respect to the shaft, meshes with a ring gear 83 surrounding and fixedly secured to the upper spider 39, and through which rotary movement is imparted to this spider. The gear ratios between the two ring gears and their driving pinions, both mounted on the shaft 74, being equal, the upper and lower spiders 39 and 44 are driven at the same speed in a counter-clockwise direction, viewing plan sections of the machine.

The shaft 61 is also provided with a worm 84 meshing with and driving a worm wheel 85 keyed to a short hollow shaft 86, mounted in suitable bearings 87, the gear 85 being preferably enclosed in a housing 88 containing an oil bath for lubrication purposes. A vertical shaft 89, splined to the hollow shaft 86, is rotatably driven thereby and is also capable of vertical adjusting movements relatively thereto. This vertical shaft extends upwardly through the center column 34 and is journaled at its upper end in a bearing 91 carried by the overhanging portion of the side column 33. A gear wheel 92, fixedly secured by a key 93 to the shaft 125

89 and resting upon the upper end of the center column 34, limits downward movement of the shaft 89, while upward displacement is prevented by a collar 94 fixed by a set screw 95 to the shaft 89 immediately beneath the lower end of the center column. It will be apparent, therefore, that vertical shaft 68 actuates certain cams, the function of which will be later explained, shaft 74 drives the upper and lower spiders 39 and 44, while shaft 89 revolves the chuck spindle driving gear 92.

Another gear wheel 96, fixed upon shaft 61, meshes with a gear 97 carried by a shaft 98, on the outer end of which is mounted a hand-wheel 99, by which the machine may be manually turned over when desired.

Height adjustment.

In order to accommodate the machine to cans of various heights, it is necessary that the vertical distance between the lower spider 44, which carries the can supporting plates, and the upper spider 39, which carries the spindle chucks between which and the supporting plates the can bodies are clamped, be capable of adjustment and regulation. With this end in view, I have provided mechanism by means of which the upper spider may be vertically adjusted relatively to the lower, and which will now be explained.

Referring particularly to Fig. 3, it will be observed that the supporting member 36, which through the ball bearings 35 carries the center column 34 upon which the upper spider 39 is carried, is circumferentially screw threaded, as indicated at 101, and is received in and supported by an interiorly threaded supporting ring 102 carried upon the top of the machine base 25. The member 36, while capable of vertical movement relatively to the frame, is retained against rotative movement by a key 103, projecting inwardly from the supporting standard 42 into a vertical groove 104, formed at one side of the member 36. It will be manifest, therefore, that rotative movement of the ring 102 will, through the threaded engagement with the supporting member 36, cause this member and the standard 34 carried thereby, and also the upper spider 39 mounted on this standard, to partake of vertical adjusting movements relatively to the lower spider 44. This rotary movement of the ring 102 is imparted thereto by a pinion 105 meshing with gear teeth upon the periphery of the ring. This gear is manually operated from a crank or handle 106 at the front of the machine, through the intermediary of a pair of bevel pinions 107.

The lower member 31 of the side column is, as previously noted, telescopically disposed within the supporting pedestal 29, and

this column also is vertically adjustable synchronously with the center column 34. With this end in view, the telescoping lower portion of the column 31 is provided with external screw threads 108 meshing with a surrounding adjusting ring 109, also supported upon the base 25. To hold the column against rotation while permitting of vertical adjusting movements, a spline 111 is disposed in a groove 112 extending vertically of the column, this spline being secured by screws 113, or otherwise, to the interior of the pedestal. The adjusting ring 109 is provided with circumferential gear teeth, which mesh with an idler gear 114 mounted intermediate this ring and the ring 102, and meshing with both. The rings 102 and 109 being of equal diameters and geared together, it will be manifest that upon manipulation of the adjusting crank 106 both the center and side columns will be simultaneously and vertically adjusted equal amounts so as to secure the requisite spacing between the upper and lower spiders, and at the same time maintain the requisite driving relation between the various mechanisms. The adjustment is very simple, may be very quickly, easily and accurately performed, and the parts remain automatically locked in adjusted position by reason of the low pitch threaded connection between the adjusting rings and the parts with which they respectively engage. During vertical adjusting movements, the shaft 89 telescopes within the shaft 86, the shaft 68 similarly telescopes within the shaft 65, and shaft 74 remains vertically stationary, but the splined connection between this shaft and the driving pinion 82 permits this pinion to slide vertically of the shaft as the side column is moved upwardly or downwardly.

Can body feeding and spacing.

The can bodies 115, either unequipped with ends or provided with bottoms only, and filled or unfilled, as the case may be, are placed manually or are delivered from the preceding machine in the line onto the outer end of the feed table 26. The top of this table is provided with adjustable side pieces 116 between which the cans are fed along by an endless conveyor 117, comprising, as shown in Figs. 1, 9, and 10, a series of pivotally connected links 118, each equipped with a head or plate 119 adapted to travel along the upper surface of the table, which is centrally slotted to accommodate the links of the conveyor which are trained over a driving sprocket 121 fixed on a shaft 122 (Figs. 1 and 9) and at the other end of the table over an idler sprocket 123. The rear end of the shaft 122 is provided with a gear 124 meshing with and driven by a gear 125 fixed on a shaft 126

which is also equipped with a sprocket wheel 127 driven by a sprocket chain 128 from a driving sprocket 129 fixed upon a shaft 131, to which is also fixed within the base of the machine a gear wheel 132, which meshes with and is driven by the gear 97 on the shaft 98. The conveyor is therefore continuously operated to feed the can bodies in a continuous movement from the receiving end of the feed table toward the mechanism for operating thereon located at the opposite end of the table.

The can bodies are fed onto the conveyor in indiscriminate spaced relation, but before they reach the delivery end of the conveyor they are automatically and accurately arranged in predetermined spaced relation so that they will each arrive at the truing up star wheel at the proper time. For the purpose of spacing the bodies on the conveyor, a spacing star wheel 133 is mounted at the rear of the conveyor so that its perimeter overlies the conveyor, and as the wheel revolves in a clockwise direction, viewing Figs. 4 and 18, the projections of the wheel are intruded between successive bodies, thus separating and spacing the bodies so that when they leave the wheel they are disposed in accurate and predetermined spaced relation. The spacing wheel is mounted upon the upper end of a shaft 134, which, as will be apparent from Figs. 10 and 11, is provided with a bevel gear 135, meshing with and driven by a companion gear 136 fixed upon a shaft 130, extending transversely of the feed table and provided at its other end with a sprocket wheel 137 by which the shaft is driven through a sprocket chain 138, trained over a driving sprocket 139 on the shaft 122. The tension on chain 138 is regulated by means of an adjustable idler 141.

For the purpose of initially stopping the bodies so that they will not jam against the spacing wheel, I have provided a stop finger 142, adapted to be reciprocated through the front wall 116 of the feed table into and out of the path of the advancing bodies on the conveyor. This stop finger is adjustably clamped by means of a screw 143 into the split upper end of a lever 144, fulcrumed at 145 upon the side wall of the feed table, and provided intermediate its ends with a cam follower 146, which is urged against the face of a cam 147, carried upon the shaft 130. In order to provide for adjustment of this cam to properly time the movements of the finger, the cam is provided with arcuate slots 148 through which bolts 149 extend, and by which the cam is clamped to the outer face of the sprocket wheel 137. The cam follower is urged against the face of the cam 147 by a tractile spring 151, and when a low portion of the cam travels be-

neath the follower, the finger 142 is projected into the path of an advancing can body. The body is stopped by this finger until the preceding body has been spaced therefrom by the spacing wheel, whereupon the finger is withdrawn, permitting the body to be advanced by the conveyor into engagement with the next depression in the spacing wheel. It will be apparent, therefore, that the advancing bodies are initially stopped by the stop finger and held for a predetermined period against movement, whereupon the finger is withdrawn and the body is permitted to advance and be properly spaced with respect to the preceding body by action of the spacing wheel.

Cap feeding.

The can ends or caps 152 are stacked in a magazine 153, Figs. 4, 18 and 19, rearwardly of the feed table, the magazine being mounted upon a bracket or shelf 154, supported from the machine frame. The caps are fed, one at a time, from the bottom of the stack and are advanced along the shelf toward the spider 39.

Mechanism for feeding the caps comprises a slide member 155 adapted to reciprocate in guideways formed in the shelf 154, the slide being provided with a plurality of feed dogs 156, the forward ends of which are normally urged into the position shown in Fig. 19, by coiled expansion springs 157. A pair of tapered knives 158 are adapted, upon return movement, or movement of the slide to the left, viewing Fig. 19, to enter between the lowermost cap in the magazine and the next above it, thereby separating the lowermost cap from the others, as shown in Fig. 19, so that upon forward movement of the slide the cap is engaged in the rearmost dog 156 and moved forwardly along the shelf to the intermediate position shown. The slide is then retracted, the dogs upon rearward movement being adapted to tilt downwardly and pass beneath the caps, and upon the next forward movement the previously removed cap is carried to the extreme position shown at the right in Fig. 19, wherein it is engaged in the pocket of the upper spider 39. A holding dog 159, mounted on the shelf, prevents return movement of the cap from this position.

The slide 155 is reciprocated by means of a lever 161 adjustably connected with the slide by a clamping bolt 162 in conjunction with a nut 163 thereon, which clamps against a collar 164. The lever is fulcrumed at 165 in the box 32 carried by the side column, as will be apparent from Fig. 4, and the other arm of the lever is equipped with a cam follower 166, which is held against the perimeter of the cam 71, Figs. 2 and 4, by means of a tractile spring 168. At each revolution

of the cam 71 the bell crank lever 161 is oscillated to reciprocate the cap feeding slide.

No can, no cap.

5 In order to prevent the feeding of caps to the machine when no bodies are being fed, the cap feeding mechanism is placed under the control of the advancing can bodies, 10 and upon failure of bodies, the cap feeding mechanism will be rendered inoperative by disconnecting a portion thereof from the reciprocating slide. Referring again to Fig. 19, it will be observed that the 15 slide 155 comprises a forward portion carrying the forward dog 156, and to which the operating lever 161 is attached, and also a rear portion 169 slidably associated with the forward portion and carrying the rear 20 dog 156, which removes the caps from the magazine. The rear portion 171 of the slide member to which the actuating lever 161 is connected has pivotally mounted thereon at 172 a rearwardly extending tail 25 173 comprising a shoulder 174 adapted to engage the rear end of the slide portion 169 by which this slide portion is moved forwardly with the other portion, and a cam extension 175. An expansion spring 30 176 interposed between the forwardly projecting end of the tail 173 and the member 155 normally retains the tail in the position shown in Fig. 19, so that the rear slide member 169 will be carried back and forth by 35 the forward member 155.

A longitudinally movable bar or shaft 177 extending transversely of the shelf 154, has fixed thereon a collar or roller 178 normally held by an expansion spring 179 in 40 the path of the inclined cam 175 on the tail 173. If, upon reverse movement of the slide and tail, that is, movement to the left viewing Fig. 19, the collar 178 is in the path of the inclined cam 175 of the tail, the tail 45 will be depressed, thereby releasing the driving shoulder 174 from engagement with the rear end of the slide member 169, so that upon the next forward movement of the slide member 155, the member 169 will remain 50 stationary. Under these circumstances, no caps will be fed from the magazine by the rear dog 156.

The position of the collar 178 is, however, 55 determined by the presence or absence of a can body just rearwardly of the spacing wheel. At this point an arm 181, adjustably mounted upon a vertical rock shaft 182, (Figs. 9 and 18), has a cam shaped extension 183 normally projecting into the path 60 of the advancing can bodies. Another arm 184, fixed to a lower end of shaft 182, is normally urged toward the right, viewing Fig. 18, by a spring 185 to project the arm 181 into the path of the cans. A swivelled 65 link 186 connects the outer end of arm 184

with the bell crank lever 187, fulcrumed at 188, the arm 189 of this lever being adapted to bear against a second collar 191 fixed on the shaft 177.

When no can is engaged with the arm 181, 70 the parts will be held by springs 185 and 179 in the normal position shown in Fig. 18. At each return movement of the slide member 155, the tail 173 will be depressed by the roller 178, thus disengaging driving 75 connection with the rear slide member 169. No caps will therefore be fed from the magazine to the machine. When, however, the arm 181 is rocked in a counter-clockwise direction by engagement of a can body with 80 the cam 183, the bell crank lever 187 will be rocked in a clockwise direction, viewing Fig. 18, thereby through its arm 189 moving the shaft 177 against the action of the spring 179 to carry the roller 178 out of the path 85 of the returning tail 173, thereby permitting the tail to be rocked under the action of spring 176 so as to engage the shoulder 174 with the slide member 169, whereby the 90 slide is carried forward to remove a cap from the magazine upon the next actuation of the lever 169. It will be apparent, therefore, that each succeeding can body will actuate the lever 181 so as to move the roller 178 out of the path of the tail and permit the feeding 95 of a cap. In the absence of a can body, however, the various parts will be held in normal position, as previously explained, thereby disconnecting the rear slide member 169 from the driving mechanism and preventing the feeding of a cap. 100

Cap holding.

During their travel from the magazine to the upper spider 39, the caps are held against 105 upward displacement by a pair of plates 191 and 192 beneath which the caps travel along the shelf. The spider 39 is so timed in its movements with respect to the cap feeding mechanism that one of the pockets 193 110 of the spider will be disposed in alignment with an advancing cap and in position to receive the same, as illustrated in Fig. 18. Reverse movement of the cap from the pocket is prevented, as previously mentioned, by 115 the holding dog 159. The shape of these pockets 193 on the upper spider 39 is best shown in Figs. 18, 20 and 21, from an inspection of which it will be observed that each pocket has a cutaway portion 194 flanked on either side by a holding portion which 120 comprises a groove 195 adapted to receive a cap, and by the bottom of which groove the cap is supported. Beneath this groove the pocket comprises a can flange receiving portion 196, and below that a smaller can body receiving portion 197. A can cap positioned in the groove 195, as previously explained, 125 is carried by the spider as it revolves in a clockwise direction in position to be dis-

posed above and in alignment with a can body which is fed to the spider by mechanism which will later be described.

During its travel with the spider, the cap 5 is pressed down against the supporting shoulder of the groove 195 and clamped against displacement from the pocket by a clamping rod 180 (Fig. 8) carried by the upper spider 39 and forced downwardly in 10 to clamping engagement with the cap by an upper stationary cam 190. The detailed construction of this mechanism will be explained more fully in connection with the chuck spindle structures.

15 *Rounding up the bodies.*

As the can bodies in predetermined spaced relation approach the delivery end of the feed table, they are successively engaged in 20 the peripheral pockets 198 of a star wheel 199, Figs. 1, 4 and 18. This wheel is carried upon the upper end of a shaft 201, equipped at its lower end with a worm wheel 202 meshing with and driven by a 25 worm wheel 203 on the shaft 126 (Fig. 9). The rotation of the star wheel is so timed with respect to the advancing can bodies that a body is received in each pocket 198 and is carried by the wheel as it revolves 30 in a counter-clockwise direction, viewing Fig. 4, into a companion pocket 193 on the spider wheel 39. The rear wall 116 of the feed table is curved as indicated at 204, Fig. 18, to permit of the arcuate movement 35 of the can bodies under the influence of the wheel 199.

The pockets 198 of the star wheel 199 are complementary to the pockets 193 of the spider wheel, except that on the star wheel 40 no provision is made for accommodation of the can caps. Each star wheel pocket therefore comprises a can flange receiving portion 205 complementary to the portion 196 of the star wheel pocket, and a can body 45 receiving portion 206 complementary to the body receiving portion 197 of the spider wheel pocket. As the star and spider wheels revolve, the pockets thereon are moved into opposed relation, thereby completely encircling the can bodies so that by 50 the conjoint action of the opposed pockets the bodies and the flanges are rounded up and brought into truly circular form, and when the bodies are now elevated into engagement with their respective caps disposed in the grooves 195 of the pockets immediately above the bodies, the flanges of 55 the bodies, being held by the pockets in truly circular form, will enter the down-turned flanges of the caps which are to be 60 double seamed thereto. It will be apparent, therefore, that even should some of the bodies be considerably distorted so that they 65 are not circular in form, the action of the cooperating pockets on the star and spider

wheels will restore the bodies to circular form and permit them to readily enter the downwardly extending flanges of the caps positioned on and carried by the spider wheel above the can bodies.

70

Lifting the bodies and caps.

The body conveyor 117 being on the same level as the top of the lower spider 49, it will be manifest that as the bodies are moved 75 by the star wheel 199 from the conveyor, they are slid onto and supported by this lower spider. Referring now to Figs. 3 and 8, it will be observed that the lower spider is equipped near its periphery with a plurality of, in the present instance ten, can body supporting plates 207, each of which is carried upon a rotatable spindle 208, having a convex bottom bearing end 209, which rests upon the convex upper face of a bearing button 211, secured by a pin 212 extending into a vertical slot in the button so that the button is capable of vertical movement, but is retained against rotation. This pin extends inwardly from a sleeve or hollow 80 shaft 213 within which the spindle 208 projects, and the button is yieldably supported in this sleeve beneath the spindle upon a coiled expansion spring 214. The sleeve 213 is vertically reciprocable in a 85 bored bearing 215 formed in the spider 44, and is held against rotation therein by a roller 216 engaged in a vertical slot 217 formed in the lower end of the bearing. The lower portion of the sleeve is shaped 90 to provide a bifurcated head 218 in which upon a shaft 219 is mounted a roller or 95 cam follower 221, adapted to travel upon a circular cam 222 surrounding the base of the standard 42. As the spider revolves, 100 the rollers 221 will travel up the rise in the cam 222, thereby lifting their respective cam supporting plates 207 from the position shown at the right in Fig. 8 to that shown at the left. This upward movement 105 elevates the can body into engagement with its respective cap so that the flange of the body enters the flange of the cap, whereupon further upward movement of the body carries the cap upwardly therewith into engagement with the rotating can spinning chucks, which will now be described.

Spinning the bodies and caps.

Referring now to Figs. 3, 6 and 8, it will 120 be observed that in the upper spider 39 and in vertical alignment with the body supporting plates 207 there are rotatably mounted a series of hollow chuck spindles 223, each carrying at its lower end a can cap engaging chuck 224, shaped on its lower face to fit the top of the cap. Upward thrust upon the chuck and spindle exerted by upward pressure of the body and cap produced by the action of the cam 222 upon the lifting

rollers 221, is absorbed in the anti-friction roller bearings 225 with which each spindle is equipped. The clamping rods 180, previously mentioned, extend centrally through their respective spindles, and at its lower end each rod has slidingly secured thereto by a pin 226 a head 227 provided with slots 228 into which said pin projects. An expansion spring 229 normally urges this head 227 downwardly so that when the rod is depressed, the head will extend downwardly beyond the chuck in position to engage the center of the cap, which has just been fed into a pocket of the spider. Each rod is normally held in its uppermost position by an expansion spring 231 surrounding its upper end and interposed between the top of the spindle 223 and a head 232 pinned to the rod. The stationary arcuate cam 190 (Figs. 1, 2, 8 and 14) is carried by spokes 233 radiating from a head 234 which is securely bolted to the hub 235, formed at the end of the side column member 33. This cam is provided with an active portion 230 (Fig. 2) which is adapted to depress a rod just after a cap has been fed into a spider pocket so that the head 227 is yieldingly forced downwardly upon the cap to clamp it in the pocket and prevent displacement therefrom during the travel of the cap to a position over its respective can body. The rod travels off from this active portion of the cam approximately at the time that the elevation of the can body begins, and when the body and cap are fully elevated into engagement with and clamped against the spindle chuck 224, the rod is free to assume the elevated position shown in Fig. 8, permitting the body and cap to be clamped between the chuck and the supporting plate 207. The spring 214 beneath the plate provides a resiliency for the clamping action between the chuck and supporting plate which obviates any danger of injury to the machine or can body which might result from slight variations in the length of the bodies, if no compensation for such irregularities were provided.

Each spindle has keyed to its upper end a pinion 236 which meshes with and is driven by the gear wheel 92 on the shaft 89, and this pinion is locked against accidental displacement by a split lock nut 237 including a set screw 238 by which the locking action is secured. Since the spiders, and consequently the spindles, are revolved in a clockwise direction, viewing Figs. 4 and 6, and the wheel 92 is revolved in a counter-clockwise direction, it will be apparent that a high speed of rotation will be imparted to the spindles, not only as the result of the high gear ratio between the gear wheel 92 and the spindle pinions 236, but also because of the fact that the spindles are traveling as

a whole with the spiders in a direction opposite to that of the gear wheel. When, therefore, a can body and cap have been lifted into engagement with a rapidly revolving spindle chuck and have been securely clamped thereto, the cap and body will partake of the rotating movements of the spindle and will be rapidly revolved or spun together with the supporting plate, which has its rotative bearing upon the convex button 211 upon which the convex end 209 of the plate spindle rests. The cans with the caps thereon will therefore be rapidly spun upon their own axes as they are carried forward by the revolving spiders to the seaming mechanism, which will now be described.

Seaming mechanism.

Instead of providing for each spindle chuck carried by the spiders a pair of seaming rolls with mechanism for revolving the same around the axis of the can bodies and for moving the rolls radially toward and from the bodies, my present invention contemplates the passing of the spinning bodies and caps thereon past seaming rolls disposed in the path of travel of the advancing caps. When the rolls are arranged in pairs as here illustrated, the spacing of the rolls is somewhat less than the original diameter of the can caps; consequently, as the rapidly spinning caps are carried into engagement with these freely rotatable rolls, the edges of the caps are forced downwardly and inwardly into a seam formation until the diameter of the caps has been reduced sufficiently to permit the passage of the cap between the rolls. By this construction the usual complicated mechanism for moving the seaming rolls radially and for revolving them bodily around the caps is eliminated, and the bodies and caps are permitted to be fed by continuous motion past the relatively fixed seaming rolls, whereby the seaming operations are performed much more rapidly and with less consumption of power than heretofore.

Furthermore, in prior machines each can has been operated upon by one set of rolls, and if an imperfect can is delivered from the machine, it is difficult to ascertain which of the various sets of seaming mechanisms is out of order. The maintenance of all of the seaming mechanisms in proper working order has also been a considerable task. In my present invention, however, all the cans are operated upon by the same seaming mechanism, and if a leaky can is delivered from the machine, the difficulty can be very speedily corrected. Furthermore, the can receiving pockets on the spider of previous machines have necessarily been spaced apart a considerable distance in order to allow room for rotation of the seaming rolls be-

tween the various pockets, necessitating, therefore, a wide spacing apart of the bodies, which resulted in a slowly operating machine. In my present invention the revolving seaming mechanisms for the individual pockets having been entirely abolished, the pockets can be disposed closely together and the can bodies can be fed to the machine in closely spaced relation, which enables a much greater production by the machine without operating the various parts at extremely high speed.

While any desired number of seaming rolls arranged either in series or in pairs past which the can bodies and caps are fed are contemplated by my invention, I have shown in the present instance for the purpose of illustrating the principles of the invention, two pairs of such rolls. These pairs are adapted, as will be later apparent, to travel with the can bodies, but at a slower speed, until the caps are seamed sufficiently to be forced between the rolls, whereupon the rolls are moved bodily in the opposite direction to dispose them in operative position with respect to the next succeeding can and cap. It should be understood, however, that my invention comprehends mounting the seaming rolls either singly or in pairs stationarily so that they receive no movement but remain fixed while the cans are successively brought into cooperative relation therewith.

Referring now to Figs. 1, 2, 4, and 8, it will be observed that just at the left of the rounding-up star wheel 199 there is mounted a set of seaming rolls comprising rolls 239 and 241, constituting one pair, and rolls 242 and 243, constituting the other pair. The outer rolls 239 and 242 are rotatably mounted in radially adjustable blocks 244 (Fig. 8), each having a downwardly extending threaded lug 245 engaging an adjusting screw 246 journaled in a housing 247 suspended from a supporting ring 248. Each screw 246 is yieldingly held in the position shown in Fig. 8 by a coiled expansion spring 249, which permits yielding outward movement away from the can body in case excessive strain is imposed on the seaming roll. Injury to the seaming mechanism is thereby obviated. The outer end of the screw 246 is shaped to receive a wrench, as indicated at 251, by which the roll may be adjusted and the parts are retained in adjusted position by a pin 252 inserted in the slotted end of the screw.

The inner roll 241 is similarly mounted in an adjustable block 253 adapted to be radially adjusted by means of a screw 254, similarly to the adjustment just described. This block 253 is mounted for radial adjustment on an inner supporting ring 255, which will be later described.

The pair of rolls 239 and 241 is adapted

to perform the first seaming operation which is disclosed in Fig. 23. In other words, the can and cap as they approach the first pair of rolls are shaped as shown in Fig. 22, but when they have been subjected to the action of the first pair of rolls sufficiently to enable the body and cap to pass between the rolls, the can flange and the cap have been bent and spun by the rolls into a partially formed seam, indicated by reference character 256 in Fig. 23. The second pair of rolls 242 and 243 is set closer together than the first pair, and as the cans are subjected to the action of these rolls, the partially formed seam of Fig. 23 is converted into the completed seam indicated by reference character 257 in Fig. 24.

While, as previously stated, the seaming rolls may be stationarily mounted relatively to the travel of the can bodies, I prefer, in order to increase the speed of the machine, that they be relatively movable with respect to the advancing cans; that is, that they move with the cans, but at a slower speed than the cans, for a limited distance, whereupon as the cans pass between the rolls, the rolls will be quickly moved in a reverse direction to immediately engage with the next succeeding can. The time during which the seaming rolls are out of operation, or in other words, not operating upon a can, is thereby reduced to a minimum.

Referring now to Fig. 1, it will be observed that the outer seaming rolls 239 and 242 are carried by a ring 248 surrounding the lower portion of the upper spider 39 and supported by a ring 258 carried at the bottom of said spider, as will be apparent from Fig. 8. The ring 248 is made in segments bolted together at 259 and 261 (Fig. 1), so as to loosely embrace the upper spider. The inner rolls 241 and 243 of each pair are carried by an inner ring 255 surrounding the center column 34, this ring being also made in two parts secured together by bolts 262 (Fig. 4). An arm 263 extending radially from the inner ring is connected, as will be apparent from Fig. 4, by a link 264 with a lever 265 fulcrumed at 266 in the housing 32 and provided with a cam follower 267 engaging in a cam track or groove formed in the end face of the cam 72 mounted on the shaft 68. This cam is so shaped that just after a can body and cap have passed between the seaming rolls, the ring 255 will be oscillated in a counter-clockwise direction to bring the seaming rolls into engagement with the next succeeding body and cap. Thereupon the rollers will travel forwardly in engagement with the cap but at a slightly slower speed than the cap, so that the spinning can cap is forced against the rollers to effect the seaming operation, and finally when the diameter of the cap has been sufficiently reduced, the cap and body pass be-

tween the rolls, whereupon the rolls are again swung in the opposite direction into engagement with the following cap.

The outer ring 248, carrying the outer 5 seaming rolls of each pair, receives a similar and equal movement since the two rings are connected together. Referring now to Figs. 4, 14, and 15, it will be observed that the arm 263 on the inner ring is provided 10 with a radially extending boss or lug 269 disposed between a pair of ears 271 formed at the lower end of an arm 272 depending from the ring 248. Angular adjustment between the rings to dispose the inner and 15 outer seaming rolls of each pair in proper position with respect to the advancing cans is effected by means of adjustable abutment screws 273 threaded through the ears 271 into engagement with opposite faces of the 20 lug 269. Through this connection both the inner and outer seaming roll carrying rings are associated as a unit and the relative positions of the rings and the seaming rolls of each pair may be adjusted when occasion 25 requires.

Lowering the cans.

During the operation of the seaming rolls upon the advancing caps, the can bodies and 30 caps are clamped together between the supporting plates 207 and the spinning chuck heads 224, as previously explained. After the cans have passed the seaming mechanism, a depression on the lifting cam 222 permits 35 the plates 207 to lower by gravity. For the purpose of ejecting the caps from the chuck heads 224, the upper cam 190 overlying the upper ends of the rods 180, is provided with a second active portion 274 (Fig. 1), which 40 imparts a downward thrust to the rods 180 as they travel there-beneath, thereby disengaging the seamed cap from its revolving chuck head. As the can and the plate 207, upon which it is supported, are lowered, a 45 downwardly extending peripheral flange 275, depending from the plate 207, engages a shoulder 276 formed in the plate socket of the lower spider 44, as is shown at the right in Fig. 8. The engagement of the 50 flange with this shoulder acts as a brake to counteract the spinning of the plate and bring the same with the can thereon to rest.

While ordinarily the supporting plates and the cam followers 221 will lower by 55 gravity, as soon as permitted by the cam 222, I have made provision, as will be apparent from Figs. 3, 8 and 13, for positive lowering of the cam followers and the hollow shafts 213 carried thereby. Upon the inner 60 end of each shaft 219, carrying the followers 221, I have also mounted a cam follower 277 adapted to engage beneath a cam 278 mounted upon one side of the standard 42. As the rollers 277 are moved successively 65 beneath this cam, they will be positively

depressed thereby to insure the lowering of the supporting plates into a position flush with the upper face of the spider 44 for the subsequent reception of a can body.

Can inspection.

It may occasionally be desirable to inspect a can after the first seaming operation in order to determine whether the first pair 70 of seaming rolls is properly adjusted, and to enable this inspection the lifting cam 222 is provided between the first and second sets 75 of seaming rolls with a removable section 278, Figs. 1, 2 and 3, pivoted between ears 279 extending outwardly from the cam, 80 upon a pin 281. This section is normally locked in operative position, as shown in Fig. 3, by a removable pin 282. Upon removal of this pin, the cam section 278 will 85 drop, permitting the cam supporting plate and the can thereon to lower so that the seam produced by the first set of rolls may be inspected. The parts are then restored to normal position by depressing a handle 283 fixed to the section 278, thereby elevating the section and the mechanism supported 90 thereby to normal position, in which position the section is then locked by reinsertion of the locking pin 282.

Cap marking.

For the purpose of providing the caps with a mark consisting of a letter, figure, or other indicia, by which the origin of the cans or the date on which they were filed, or other desired information may be ascertained, I have provided mechanism for applying such indicia to the caps, which will 100 now be described.

Referring to Figs. 16, 17 and 18, it will be observed that laterally of the chute along which the caps travel from the magazine 153 to the spider 39 there is mounted a bracket 284 projecting over the chute and carrying at its outer end a marking device 285, positioned over the center of a cap when such cap is stopped in its intermediate position between the magazine and the spider. This marking device is normally held in the 110 elevated position shown in Fig. 17 by a coiled expansion spring 286. A hammer comprising a head 287, a flexible shank 288, and a lever 289, to which the shank is secured, is pivoted at 291 so as to dispose the hammer head directly over the marking device 285. The rear end of the lever is provided with a follower 292, which is urged into engagement with the cam 73, previously mentioned, by an expansion spring 293. The cam includes an abrupt depression 294 and a long dwell. The parts are so timed 115 that when a cap is disposed beneath the marking device, the cam depression 294 will move into position above the follower 292, permitting a sharp downward movement of 120

the hammer head under the influence of the spring 293 to thereby force the marking device into marking engagement with the cap, as shown in Fig. 16. The cam thereupon lifts the hammer into the inoperative position shown in Fig. 17, in which position it is retained until the next marking operation is performed.

Operation.

10 The operation of a machine embodying my invention is briefly as follows. The can bodies are delivered to the conveyor, upon which they are spaced in predetermined relation by the spacing mechanism, and are then engaged between the complementary pockets of the star wheel 199 and the upper spider 39, whereby the bodies are rounded up. The caps are fed from the magazine 15 first to an intermediate position where they are marked, and then to the spider wheel where they are supported in the pockets above the can bodies, in which position they are held by the clamping rods 180. In the 20 event of failure of a can, the cap feeding mechanism is rendered inoperative.

After being rounded up, the can bodies are lifted into engagement with their respective caps, and then still further elevated with the caps to clamp the bodies and caps between the supporting tables 207 and the revolving chuck heads 224. The spindles are rapidly revolved by means of the gear wheel 92, which is rotating in a direction opposite to the rotation of the spider. A rapid revolving or spinning movement is thereby imparted to the cans which are supported upon the plates, the spindles of which are carried upon the convex buttons 30 211. The spinning cans and bodies are then moved by the spider into engagement with the first pair of seaming rolls by which the first seaming operation is performed. When the diameter of the cap has been sufficiently reduced, the cap and body will pass between the rolls and into engagement with the next pair of rolls by which the final seaming operation is performed. Both sets of seaming rolls travel with the cans during the 40 50 seaming operation but at a slower speed, and after each seaming operation is performed, the rolls are moved in the opposite direction to engage the next succeeding cans with a minimum loss of time.

55 The bodies with the caps seamed thereon are then lowered, the caps being ejected from their chucks by the rods 180. The lifting rollers 221 are restored to normal position by the cam 278, and as the bodies 60 continue their movement with the spider, they are eventually delivered into the delivery chute 28.

While I have shown and described in detail a preferred embodiment of my invention, it should be manifest that the invention,

tion is not limited to the details which have been selected for illustrative purposes merely, but is capable of embodiment in machines differing materially in their construction and mode of operation from that shown and described without departing from the essence of the invention, as defined in the following claims:

I claim:

1. In a seaming machine, the combination of a plurality of seaming rolls stationarily disposed relatively to each other but movable together as a unit, and means for moving a can body and cap past said rolls in a continuous movement and in cooperative relation thereto to effect the seaming of the cap onto the can body by said rolls. 75

2. In a seaming machine, the combination of a plurality of seaming rolls mounted for limited movement parallel with the path of an advancing cap, means for revolving a can body and a cap disposed thereon, and continually moving means for moving said revolving body and cap past said rolls and in engagement therewith, whereby the cap is secured to the body. 80 85

3. In a seaming machine, the combination of a pair of seaming rolls mounted in predetermined spaced relation, and means for moving a revolving can body with a cap disposed thereon in a continuous movement between said rolls and in engagement therewith, whereby the cap is secured to the body. 90 95

4. In a seaming machine, the combination of means for continuously feeding a vertically disposed can body and a cap thereon in a transverse direction, and means disposed in the path of travel of said cap and movable parallel with the path of travel of the cap for securing the cap to the body during the travel of said cap and body past said means. 100

5. In a seaming machine the combination of a pair of seaming rolls mounted in spaced relation, means for feeding a can body and cap between said rolls and in engagement therewith, and means for permitting said rolls to travel with said body and cap for a limited distance but at a slower speed than the body and cap. 110

6. In a seaming machine, the combination of means for advancing a can body with a cap disposed thereon, means for revolving said body and cap during such advance, seaming mechanism disposed in the path of travel of the advancing caps and means for bodily moving said seaming mechanism along the path of travel of said caps in a direction opposite to the travel of the caps. 115 120

7. In a seaming machine, the combination of means for advancing can bodies with caps disposed thereon, means for revolving said bodies and caps during such advance movement, seaming mechanism disposed in the path of travel of said advancing caps against which the caps are urged, and means for 125 130

moving said seaming mechanism bodily back and forth along the path of travel of said bodies and caps.

8. In a seaming machine, the combination of means for advancing can bodies with caps disposed thereon, seaming rolls disposed in the path of travel of the advancing caps to engage the perimeters thereof, said seaming rolls being normally immovable radially of the caps, and means for moving said rolls bodily in a direction substantially parallel with the path of the advancing bodies and caps.

9. In a seaming machine, the combination of continuously operating can body and cap advancing mechanism, and can seaming means fixedly mounted a predetermined distance from the path of travel of the centers of the advancing caps by which said caps are secured to the can bodies during their travel past said seaming means, said seaming means being movable with said caps.

10. In a seaming machine, the combination of rotatable means for advancing can bodies with caps disposed thereon, seaming rolls mounted at fixed radial distances from the axis of said advancing means and in the path of travel of the advancing bodies and caps, and means for bodily oscillating said rolls parallel with the movement of said advancing means.

11. In a seaming machine, the combination of a rotatable spider provided with can body and cap receiving pockets, means for revolving can bodies and caps in said pockets, seaming rolls mounted in the path of travel of the advancing bodies and caps predetermined distances from the axis of said spider, and means for oscillating said rolls bodily back and forth along the path of travel of the bodies and caps.

12. In a seaming machine, the combination of a rotatable spider provided with peripheral pockets, means for positioning can bodies and caps in said pockets, seaming roll supporting means mounted to oscillate concentrically with said spider, seaming rolls carried by said means in the path of travel of the advancing bodies and caps, and means for adjusting said rolls radially of the spider.

13. In a seaming machine, the combination of a rotatable spider provided with peripheral pockets, means for positioning can bodies and caps in said pockets, a pair of seaming roll supporting rings mounted concentrically with said spider, seaming rolls carried by the rings in predetermined spaced relation in the path of the advancing bodies and caps, means for adjusting the rolls toward and from each other, means for oscillating the rings, and means for relatively adjusting the rings.

14. In a seaming machine, the combination of a rotatable spider provided with periph-

eral pockets, means for positioning can bodies and caps in said pockets, a pair of seaming roll supporting devices, a seaming roll adjustably mounted upon each device, said rolls being disposed in the path of travel of the advancing bodies and caps, and means for angularly adjusting said rolls relatively to each other circumferentially of said spider.

15. In a seaming machine, the combination of a rotatable spider provided with peripheral pockets, means for positioning can bodies and caps in said pockets, a pair of seaming rolls stationarily mounted in spaced relation in the path of the advancing bodies and caps, means for adjusting said rolls relatively to each other radially of the spider, and means for adjusting said rolls relatively to each other circumferentially of the spider.

16. In a seaming machine, the combination of means for advancing can bodies and caps, a plurality of pairs of seaming rolls mounted in spaced relation in the path of the advancing bodies and caps, means for adjusting the rolls of each pair toward and from each other, and means for adjusting the rolls of each pair forwardly or backwardly along the path of travel of the bodies and caps relatively to the other rolls.

17. In a seaming machine, the combination of a rotatable spider provided with peripheral pockets, means for positioning can bodies and caps in said pockets, means for revolving the bodies and caps in said pockets, a pair of seaming roll supporting rings mounted concentrically with the spider, seaming rolls carried by each ring in the path of travel of the advancing bodies and caps, means for adjusting the rolls on each ring radially of the spider, means for adjusting the rings relatively to each other circumferentially of the spider, and means for oscillating said rings as a unit to move the seaming rolls back and forth along the path of travel of the advancing bodies and caps.

18. In a seaming machine, the combination of a rotatable spider provided with peripheral pockets, each pocket comprising a can body receiving portion, a body flange receiving portion and a cap receiving and supporting portion, means for feeding can bodies and caps to their respective portions of said pockets, and means cooperating with the body and flange receiving portions for rounding up said bodies and flanges.

19. In a seaming machine, the combination of a spider provided with peripheral pockets, each pocket comprising a can body receiving portion, a body flange receiving portion and a cap receiving and supporting portion, means for positioning can bodies and caps in said pockets, and a member provided with pockets having complementary

can body and flange receiving portions, whereby the bodies and flanges are rounded up.

20. In a seaming machine, the combination of a spider provided with peripheral pockets, each comprising can body and cap receiving portions, means for feeding caps into said pockets, means for feeding can bodies into said pockets, said last mentioned means being provided with complementary body pockets whereby in conjunction with the spider pockets the can bodies are rounded up, and means for elevating said rounded up bodies into the superposed caps.

21. In a seaming machine, the combination of a spider provided with peripheral pockets, means for feeding can caps thereto, means for holding the caps therein against displacement, means for feeding can bodies into the spider pockets beneath the caps, means for rounding up the bodies, means for lifting the bodies into engagement with the caps and for lifting the bodies and caps together, and means against which said caps are lifted whereby the bodies and caps are revolved.

22. In a seaming machine, the combination of a pair of normally stationary seaming rolls, means for advancing can bodies and caps between said rolls by an uninterrupted motion, means for adjusting said rolls toward and from each other, and means for yieldingly holding said rolls in adjusted position.

23. In a seaming machine, the combination of a primary seaming roll and a final seaming roll both mounted and maintained a predetermined distance from a fixed path along which can bodies and caps travel, means for advancing can bodies and caps past said rolls and in a continuous motion along said path, means for rapidly revolving said bodies and caps during their travel whereby the caps are seamed to their respective bodies by said rolls during their travel past the rolls and means for positively moving said rolls.

24. In a seaming machine, the combination of a base, a standard mounted thereon, a can body supporting spider mounted on said standard, a pair of columns projecting upwardly from said base, can seaming mechanism carried by said columns, and means for vertically adjusting said columns to accommodate the machine to cans of various heights.

25. In a seaming machine, the combination of means for supporting can bodies and caps, a pair of columns, means carried by said columns for revolving the supported can bodies and caps and for seaming the caps onto said bodies, and means whereby said columns and mechanism carried thereby may be simultaneously adjusted to ac-

commodate the machine to cans of various heights.

26. In a seaming machine, the combination of a pair of supporting columns, can body and cap spinning and seaming mechanisms carried by one of said columns, a spindle actuating cam carried by the other column and a single adjusting means whereby the vertical height of said cam and spinning and seaming mechanisms may be adjusted.

27. In a seaming machine, the combination of a base, a standard projecting upwardly therefrom, a column extending upwardly through said standard, a can body supporting spider rotatably mounted upon the standard, a spindle carrying spider mounted upon the column, can body and cap revolving spindles carried by said last mentioned spider, seaming rolls also supported from said spider, and means for adjusting said column to vary the distance between said spiders.

28. In a seaming machine, the combination of a base, a standard projecting upwardly therefrom, a can body supporting spider rotatably mounted on said standard, means for enclosing the supporting bearings for said standard, a column projecting upwardly through said standard, can body spinning and seaming mechanisms carried by said column, a threaded supporting member for said column, a supporting ring carried by said base and threadedly engaged with said supporting member, and means for rotating said ring to adjust the height of said column and the mechanisms carried thereby.

29. In a seaming machine, the combination of a base, a non-rotatable column supporting member, a ring threaded onto said member and supported by said base, a column rotatably supported by said member, and means for rotating said ring to adjust the height of said column.

30. In a seaming machine, the combination of a base, a supporting member, a column carried thereby, a bearing between the member and column, a supporting ring threaded onto said supporting member, means for holding said supporting member against rotation, and means for rotating said ring to raise and lower said column.

31. In a seaming machine, the combination of a base, a center column, a threaded supporting member therefor, a ring threadedly engaged with said supporting member and carried by said base, a side column, a ring threadedly engaged with the lower portion of said column and resting on said base, and means for simultaneously rotating said rings to simultaneously adjust said columns relatively to the base.

32. In a seaming machine, the combina-

tion of a center column, a side column, a threaded supporting member for said center column, rings threaded onto said supporting member and onto the lower end of said side column, respectively, and means for simultaneously rotating both of said rings to adjust the height of said columns.

33. In a seaming machine, the combination of a base, a side column telescopically associated with said base and threaded at its lower end, a ring supported by said base threadedly engaged with said column, a center column, a supporting member therefor, a ring threadedly engaged with said supporting member and carried by said base, a gear wheel connecting said rings, and manually operable means for rotating the rings to thereby simultaneously adjust said columns vertically relatively to the base.

34. In a seaming machine, the combination of a base, a lower spider rotatably mounted thereon, a vertically adjustable center column projecting upwardly from the base, an upper spider fixed on said center column, a shaft projecting longitudinally through the center column and movable longitudinally therewith, a vertically adjustable side column carried by the base, a shaft extending vertically in said side column, gears on said shaft for driving said spiders, a third shaft extending vertically from the base in proximity to said side column, operating mechanisms carried by said shaft, and mechanism in said base for driving all of said shafts, each of said shafts having a splined relation with driving or driven members, permitting vertical adjustments of the columns without disturbing the driving relation.

35. In a seaming machine, the combination of a base, a pair of vertically adjustable columns carried thereby, a pair of shafts supported by their respective columns, mechanisms adjustable with the columns operated by said shafts, driving mechanism in said base, and a telescopic driving connection between said mechanism and each of said shafts, permitting vertical adjustment of the shafts with their columns without disturbing the driving relation.

36. In a seaming machine, the combination of a rotatable spider provided with sockets, can body supporting plates disposed in said sockets, means for raising and rotatably supporting said plates, and means whereby rotation of said plates is stopped when the plates are lowered into the sockets.

37. In a seaming machine, the combination of a spider provided with sockets, can body supporting plates provided with downturned flanges adapted to frictionally engage in said sockets to prevent rotation of the plates when in lowered position, and means for raising and rotatably supporting said plates.

38. In a seaming machine, the combina-

tion of a spider, can body supporting plates, rotatable spindles upon which said plates are carried, and yielding means for raising and rotatably supporting said spindles, said plates being adapted to frictionally engage 70 said spider when in lowered position to thereby stop the rotation thereof.

39. In a seaming machine, the combination of a spider provided with vertically disposed bearings, a hollow shaft mounted to reciprocate in said bearings, means for preventing rotation of said shaft, a spring supported convex bearing button disposed in each shaft, a spindle having a convex end supported upon said button, and a can body supporting plate carried by the upper end of each spindle.

40. In a seaming machine, the combination of a spider provided with vertical bearings and sockets above said bearings, a hollow shaft slidably mounted in each bearing, a spindle extending downwardly into each shaft, a can body supporting plate mounted upon the upper end of said spindle, and means including a spring pressed bearing button within the shaft for yieldably and rotatably supporting said spindle, the opposed surfaces of said spindle and button being convex.

41. In a seaming machine, the combination of a spider provided with upwardly opening sockets, a bearing extending downwardly from each socket, a hollow shaft mounted to reciprocate in said bearing, a spindle rotatably mounted in each shaft, a can body supporting plate carried by the upper end of each spindle, and means for positively raising and positively lowering said shaft during a revolution of said spider.

42. In a seaming machine, the combination of a spider, a plurality of can body supporting plates carried thereby, means for raising said plates relatively to the spider, including a reciprocatory shaft for each plate and a cam follower carried by said shaft, a stationary cam for raising each shaft, and a stationary cam for lowering each shaft.

43. In a seaming machine, the combination of a spider, a plurality of spindles rotatably mounted therein, a can end engaging chuck carried by each spindle, a pinion mounted on each spindle, a gear meshing with all of said spindles, means for simultaneously and continuously driving said gear in one direction, and means for driving said spider in the opposite direction.

44. In a seaming machine, the combination of a rotatable spider, a plurality of spindles rotatably carried thereby, a can cap engaging chuck mounted on the lower end of each spindle, a pinion mounted on the upper end of each spindle, a gear meshing with all of said pinions, means for revolving said gear in one direction to simultane-

ously rotate the pinions, means for simultaneously revolving said spider in the opposite direction to increase the speed of rotation of said spindles, a holding and ejecting rod extending through each spindle, and means for depressing said rods upon rotation of said spider.

45. In a seaming machine, the combination of a rotatable spider, can body supporting plates carried thereby, vertically reciprocatory shafts by which said plates may be lifted, a cam follower at the lower end of each shaft, a stationary cam upon which said followers travel, and means whereby 10 a portion of said cam may be removed to permit the lowering of a plate for the inspection of a can body thereon.

46. In a seaming machine, the combination of a rotatable spider, a plurality of can body supporting plates mounted thereon, and means for lifting said plates, said means including a stationary cam provided with a removable portion to permit the lowering of a plate at a certain position in the 25 machine.

47. In a seaming machine, the combination of can body supporting mechanism, means including a cam for raising the same, and manually operable means for removing 30 a portion of said cam to permit the lowering of a can body supporting device.

48. A can seaming machine including a stationary cam for lifting can bodies, said cam comprising a removable section, and manually operable means for removing and 35 replacing said section.

49. In a seaming machine, the combination of a magazine for can caps, means for feeding said caps successively from said 40 magazine, including a two-part slide provided with feed dogs, and means controlled by the feeding of can bodies for disconnecting one part of said slide from its operating mechanism.

50. In a seaming machine, the combination of a magazine for can caps, means including a two-part slide provided with feed dogs for feeding caps from said magazine, means for reciprocating the forward portion 45 of said slide, a tail carried by said portion and adapted to engage the rear portion of the slide, and means in the path of movement of said tail for depressing the tail to disconnect the same from said rear portion of the slide, said means being rendered inoperative by the presence of a can body 55 in a predetermined position on the can body feeding mechanism.

51. In a machine for operating upon can bodies, the combination of a magazine adapted to contain caps, a two-part slide reciprocable beneath said magazine, a feed dog on each part, a tail carried by one part and provided with a shoulder adapted to engage

the other part and connect the two parts 65 together, means in the path of movement of said tail for depressing the same to disconnect the parts, and means operated by a can body for moving said last mentioned means into inoperative position. 70

52. In a machine for operating upon can bodies, the combination of a magazine, a two-part slide reciprocable beneath said magazine, feed dogs on said slide, a pivotally mounted member for connecting the 75 two parts of said slide, a roller in the path of movement of said member for depressing the same to disconnect the parts, a spring for urging said roller into operative position, and means including a feeler arm projecting into the path of advancing can bodies and connections between said arm and said roller whereby the roller may be moved into inoperative position by an advancing body. 80

53. In a machine of the character described, the combination of means for feeding can caps by a step-by-step movement, means for marking said caps including a marking member, and means for actuating 90 said marking member, including a hammer and a cam for actuating the hammer with a flexible shank. 95

54. In a machine of the character described, the combination of means for advancing can bodies by a step-by-step movement, a marker disposed over the path of travel of the caps, a pivoted hammer comprising a head and a resilient shank, a cam for elevating said hammer head, and a 100 spring for imparting an operative stroke to said hammer.

55. In a seaming machine, the combination of continuously traveling means for revolving a can body and cap, and seaming means normally immovable toward or from the path of the body and cap past which said revolving body and cap are moved, whereby the end is seamed to the body during the travel thereof, said means being movable 110 with the can ends. 105

56. In a seaming machine, the combination of a plurality of continuously traveling revolving chucks adapted to carry and revolve can bodies and ends, and means in the path of the traveling ends for seaming said ends in succession to their respective bodies during their travel past said seaming means, said means being movable parallel with the 115 travel of the chucks. 120

57. In a seaming machine, the combination of a series of revolving can body and end holding chucks arranged in closely spaced relation, seaming mechanism, means for causing said chucks to travel past and in co-operative relation to said seaming mechanism, whereby said ends are seamed 125 in succession onto their respective bodies

during their travel past said mechanism and means for moving said seaming mechanism relatively to said ends.

58. In a seaming machine, the combination of a series of can body and end holding chucks, a plurality of seaming rolls spaced apart substantially the distance between successive chucks, means for causing said chucks to travel in a continuous movement

10 past said seaming rolls to subject the bodies and ends on said chucks successively to the action of said seaming rolls during the travel of the bodies and means for moving the seaming mechanism relatively to the chucks.

59. In a can seaming machine, the combination of a series of revolving can body and end holding chucks, means for continuously moving said chucks, seaming mechanism past which the chucks are caused to travel, whereby the can ends are seamed in succession onto their respective bodies without interrupting their travel and means for positively moving said seaming mechanism in timed relation to the travel of the chucks.

20 60. In a seaming machine, the combination of means for advancing in a continuous motion can bodies and caps, a seaming roll mounted a predetermined distance from the path of travel of said advancing bodies and caps whereby the caps are seamed onto their respective bodies during their travel past said roll and means for moving said roll during each seaming operation.

25 35 61. In a seaming machine, the combination

of means for revolving and continuously advancing a can body and cap, a seaming roll past which said body and cap are caused to travel whereby said cap is seamed to said body without interrupting the travel of said body and cap and means for moving said roll between successive seaming operations.

62. In a seaming machine, the combination of a plurality of seaming rollers mounted and maintained a predetermined distance from a fixed path in which can bodies and caps travel, means for moving said rolls parallel with said path, means for advancing can bodies and caps past said rollers in a continuous motion in said path, and means for revolving said bodies and caps during their travel whereby the caps are seamed onto their respective bodies by said rolls during their travel past the rolls.

55 63. In a machine for operating upon can bodies, the combination of a magazine, feed mechanism for feeding caps from said magazine, including a member movable into inoperative position, a roller adapted to be disposed in the path of movement of said member for rendering said member inoperative, a spring for urging said roller into operative position, and means including a feeler arm projecting into the path of advancing can bodies whereby said roller is moved into inoperative position by an advancing body.

60 65 WILLIAM CAMERON.
